UNITED STATES PATENT OFFICE.

BEST AVAILABLE COPY

CHARLES H. BOECK, OF JACKSON, MICHIGAN, ASSIGNOR TO THE NOVELTY MANUFACTURING COMPANY, OF SAME PLACE.

DESIGN FOR AN OIL HEATING-STOVE.

SPECIFICATION forming part of Design No. 25,813, dated July 21, 1896.

Application filed April 20, 1896. Serial No. 588,388. Term of patent 7 years.

To all whom it may concern:

Be it known that I, CHARLES H. BOECK, a citizen of the United States, residing at the city of Jackson, in the county of Jackson and State of Michigan, have invented a certain new and useful Design for Oil Heating-Stoves, of which the following is a specification.

My invention relates to a design for an oil heating-stove. It relates to the entire construction of the stove, and especially to a stove constructed of sheet metal.

My invention relates particularly to the stove as illustrated in the accompanying drawings, in which—

15 Figure 1 represents a perspective view of a stove embodying my design. Fig. 2 is an enlarged top plan view of the top of the same. Fig. 3 is a side elevation of the same.

Similar letters of reference refer to similar 20 parts throughout the several views.

The leading features of my design appear in the following description.

The stove is made up of a round smooth base-ring A, supported on sheet-metal legs F 25 of the design indicated. Resting on this base is the body portion B for containing the tank or reservoir of the stove. Above this is a polished sheet-metal rim B'. Resting upon this rim B' is a heating-drum C, which is supported on the polished rim at the bottom, which rests by suitable feet on the rim B'. The top D is also formed of polished metal shaped in regular form, as indicated. The lower portion projects out beyond the sides 35 of the drum and bears a central cover portion above. Suitable perforations are indicated in the top for the passage of the heat. These perforations are not material to the

design and might be made through the sides of the top of the heating-drum C, instead of 40 through other portions of the top, without varying my design. Around the drum are suitable ornamental bands b, and a similar band appears around the body portion. A window-frame E, of bright metal, carrying the 45 usual mica sheets, is placed in the side of the heating-drum, as indicated.

I have shown no urn on the top of my stove, but wish it understood that any kind of an urn might be used in this connection. 50

Having thus described my design, what I claim as new, and desire to secure by Letters Patent, is—

1. A design for an oil heating-stove substantially as described and shown. 55
2. In a design for an oil heating-stove the base A, substantially as described and shown.
3. In a design for an oil heating-stove the body portion B, substantially as described and shown.
4. In a design for an oil heating-stove the drum C, substantially as described and shown.
5. In a design for an oil heating-stove the top D, substantially as described and shown.
6. In a design for an oil heating-stove the leg substantially as described and shown. 65
7. In a design for an oil heating-stove the window E, substantially as described and shown.

In witness whereof I have hereunto set my 70 hand and seal in the presence of two witnesses.

CHARLES H. BOECK. [L. S.]
